ABSTRACT OF THE DISCLOSURE

For contributing to the keeping of a boat or other craft afloat in an emergency, a fully organized, self-contained flotation unit is provided which includes as one of its components a rigid carrying member, adapted for quick and easy attachment to the ceiling of a compartment or room of the craft, and upon which all the other components of the unit, in fully operative association with one another, are compactly mounted.

The other components of each unit desirably comprise a tank or cylinder containing an appropriate inflating gas, such as carbon dioxide, an elastic bladder, and connecting means providing communication between the tank and the bladder, and including a supply valve, a pressure limiting regulating valve, and a pressure relief valve. The bladder is surrounded by an envelope of strong, freely flexible, inextensible woven fabric for limiting expansion of the bladder and protecting it against puncturing. The bladder and envelope, compactly folded, are contained snugly within an easy-tear container of small capacity which normally holds them to the carrier, but which tears apart in response to inflating pressure.

The connecting means between the tank and the bladder also desirably includes a distinct supply valve and heat responsive means for opening such valve in case of fire.

Provision is made for controlling a group of the units from a common remote control station, either by turning on the units singly or by turning on a plurality of the units simultaneously.

Various proposals have been made for equipping boats or other craft with one or more flotation bladders for keeping the craft afloat in an emergency. Frequently the structure of the craft has been modified to accommodate the bladders and associated mechanisms, and as a rule the several associated mechanisms have been brought into association with one another for the first time by mounting them separately on the craft and then connecting them with one another. In other instances a multiplicity of bladders have been connected to a common source of inflating gas under pressure through an elaborate system of pipes, which included a single common pipe adjacent the source, the arrangement being such that part or all of the bladders could be put out of commission before or after inflation by damage to the pipes or part of them.

It is a primary object of the present invention to provide a fully organized, self-sufficient, flotation unit which includes as one of its components a rigid carrier member adapted for quick and convenient attachment to the ceiling of a compartment or room of the craft, and upon which all of the other components of the unit, in fully operative association with one another, have been compactly mounted. With such an arrangement each unit has its own individual gas supply, the supply lines are localized and kept short, and other advantages are realized.

It is a further object of the invention to so arrange the components of a unit that the unit will be neatly

2

organized, convenient to store, handle and ship, easy to install, and inconspicuous when installed.

In referring to the units as inconspicuous, it is not meant that a unit is so small as to escape notice, but rather that it is relatively compact in its normal dimensions as compared with its inflated dimensions, that it is not unsightly, and that it can be installed in out of the way locations where it will not materially curtail or interfere with the normal use of the room or compartment in which it is installed.

To these ends, the unit desirably includes in addition to the rigid carrying member already referred to and a tank or cylinder of gas under high pressure mounted thereon, a bladder of resilient, stretchable, foldable material, also carried by the support, and connected to the tank for inflation by it when required.

The bladder desirably has considerable strength, but it can be readily punctured by a sharp object, and it can be strained in use to the bursting point unless inflation is limited and the bladder is substantially reinforced. It is accordingly a feature that the bladder, with the exception of a thickened neck portion, is enclosed in an envelope of strong, tough, flexible, readily foldable, non-stretchable woven fabric when limits expansion and deformation of the bladder, and protects it against puncture.

The bladder and envelope, if permitted to dangle from the carrier, would be awkward to store, ship and install, and would be unsightly and in the way when installed. The unit is therefore made to include a container in which the bladder and envelope are compactly folded and snugly enclosed. The container has a portion which is firmly and permanently affixed to the rigid carrier, but the remainder of the container is provided with one or more easy-tear lines, so the container will be incapable of substantially opposing inflation, and will be torn apart as the bladder expands under inflating pressure.

The connection from the tank to the bladder includes a normally closed supply valve and a constant pressure regulator to prevent over-inflation. Since the sudden loss of pressure of the gas as it enters the bladder will cause some of it to be converted to solid form (as carbon dioxide to Dry Ice), which will not at once affect the pressure regulator, but may later result in a pressure higher than is safe or desirable, a relief valve is provided in direct communication with the bladder, set for a safe pressure, but one which is higher than that of the regulator.

The supply valve may be opened by direct manual operation, or it may be manually opened by remote control. Where two or more units are employed in a system, they can be opened individually or by group action through remote control.

It is an important feature that a gas supply valve may be provided which is automatically opened in response to heat generated by fire. In this situation, if the bladder and envelope are destroyed by the fire, the gas will be poured out rapidly onto the fire.

Other objects and advantages will hereinafter appear. In the drawing which forms part of this specification, FIGURE 1 is a view in elevation in which a single illustrative flotation unit is shown in installed condition, together with an electrical system for either remote manual control, direct manual control, or automatic water level control, of the unit supply valve;

FIGURE 2 is a somewhat idealized showing of a portion of the unit of FIGURE 1 in an inflated condition;

FIGURE 3 is a plan view showing the bladder, the envelope, and a portion of the rigid support, prior to folding of the bladder and envelope, and the enclosure of them in the container;

FIGURE 4 is an electrical diagram showing both man-

ual and automatic means for bringing about inflation as required where a number of units are included in a system; and

FIGURE 5 is a transverse sectional view through a seat of a small open boat and showing how an inflation unit may be removably attached thereto.

In FIGURE 1 the interior of a compartment is shown in which a flotation unit 10, illustrative of the invention and embodying features thereof, is secured by suitable fasteners, such as screws 12, to the compartment ceiling 14. The fasteners 12 are passed upward through a carrier member 16, which may advantageously consist of a flat, rigid sheet of plywood or composition board, and which constitutes a significant part of the unit. The carrier member 16 serves as a common support for all the other components of the unit.

The unit includes a metallic supply tank or cylinder 18 which normally contains a suitable gas, preferably carbon dioxide, maintained in liquid form under a pressure suitable for that purpose. The tank 18 is held in place on the carrier by metallic straps 20 (one shown), the out-turned ends of which are secured to the carrier member 16 by screws 22.

A channel of communication is provided between the tank 18 and the thickened neck 24 of a stretchable, elastic bladder 26, desirably of rubber. The communicating channel includes tubing 28 having parallel branches 30 and 32. In one of the branches, 32, there is provided a normally closed supply valve 34 which may be operated manually or automatically for permitting inflating gas to flow from the tank 18 into the bladder 26. After passing the branched portion of the tubing, the gas flows through a settable regulating valve 35 designed to limit the pressure of the gas in the inflated bladder substantially to a predetermined, operating value, well within the limit of safety.

Since inflation of the bladder is attended by sudden expansion of the gas, and marked loss of temperature, a portion of the gas may be delivered to the bladder as Dry Ice. As the Dry Ice sublimates later, it may tend to increase the bladder pressure beyond a safe or desirable limit. A relief valve 36, set for a safe pressure, but one somewhat higher than the setting of the regulating valve, is accordingly provided in direct communication with the interior of the bladder.

In the other branch 30 of the tubing 28 a valve 38 is provided which is normally held closed by a low melting solder, but which is connected to a spring 40 that constantly urges the valve in an opening direction. If a fire occurs sufficiently near at hand to melt the solder, the valve 38 is automatically opened by the spring 40, and the gas is released for discharge into the bladder. In such a situation, however, the bladder would most probably be burned or melted away, and the gas would be discharged into the atmosphere. Since, as is well known, carbon dioxide is incombustible, will not support combustion, and is heavier than air, it will blanket and combat the fire. The flotation unit has the additional advantages, therefore, of serving as an automatic fire extinguisher.

The inflatable, stretchable bladder 26 is contained within an envelope 42 of freely flexible, strong, inextensible woven fabric, such as nylon. The envelope 42 has somewhat more superficial area than the uninflated bladder. It is stronger and tougher than the bladder, and serves effectively to protect the bladder against puncturing. It also supports the bladder from without, reinforcing the bladder, limiting the expansion of the bladder, and protecting the bladder against bursting under the strains to which the inflated bladder is subjected in an emergency. The envelope further controls to a substantial degree the shape of the inflated bladder, a feature of advantage which will be discussed at a subsequent point. The envelope and bladder may be specially reinforced for controlling the shape of the inflated bladder.

The strength and thickness of the bladder walls, the

strength and weight of the nylon, and the shape of the bladder and envelope all admit of extensive variations to meet varying needs and limitations imposed by different craft, and by craft compartments of varying size, shape and locations.

5 A typical uninflated bladder and unconfined envelope are shown in relation to one another and as if laid out over a portion of the carrier in FIGURE 3. If the bladder and envelope were permitted to dangle from the carrier or merely to hang from the bladder neck, the structure would be unsightly, could prove a substantial nuisance, and the bladder neck might be choked off to an objectionable extent. The unit would be awkward to store, handle and transport before installation, and would be likely to be damaged in transit. It is, therefore, important to make a neat, compact package of the entire unit, but in such a way that no significant resistance to inflation of the bladder will be created by the packaging means.

To this end a container is provided of relatively flimsy material, say in the form of a paper bag, having a rectangular bottom. The portion of the carrier upon which the container is to be placed may be covered with tacky adhesive. The base of the container, which may have holes of substantial size in it, may also be covered internally with tacky adhesive. The envelope 42 and the contained bladder 26, in the flat relation shown in FIGURE 3 and with the bladder neck free, are folded in along longitudinally extending lines indicated by the arrows 46-46 and 48-48. The envelope and bladder are then cross-folded successively along cross lines indicated by the arrows 50-50, 52-52 and 54-54, and placed in the container, so that the bottom of the container 44 becomes adhered to the mounting member 16 and the envelope 42 becomes permanently attached through the container base, and directly, to the mounting member 16.

The mouth of the container is then closed and sealed, to confine the bladder and envelope snugly, the neck of the bladder is connected to the tubing 28 as shown in FIGURE 1, and the bladder neck is connected to the mounting member 16 by neck embracing staples 56.

While the container is, as stated, of relatively flimsy material as compared with the bladder and the envelope, it is of adequate strength to prevent separation or disarrangement of the package components during ordinary use. Prior to installation the container may be tied snugly to the carrier member 16, though such ties should be removed upon installation. If the container is made of paper, it will be provided with a peripheral easy-tear line in the location marked 58, near the area of union with the mounting member. If of woven fabric, the container will desirably be composed of upper and lower parts united long line 58, by a seam in which weak thread is used for the stitching, capable of being readily broken by inflating pressure.

55 In FIGURE 1 a system is illustrated in which a single unit is used, the electrical control system being shown in broken lines. A source of electrical energy 60, shown as a battery, has one of its terminals connected to ground and the other connected through a conductor 62 to a terminal 64, where the circuit is divided to provide parallel conductive paths.

60 One of these paths includes a normally open switch 66, a conductor 68 and a solenoid winding 70 to ground. The solenoid armature 72 is connected to the valve 34 and is biased toward the closed position in which it is shown in FIGURE 1, but when the solenoid is electromagnetically drawn to the left to open the valve, it is desirably detained in that position by a detent (not shown).

65 The other circuit path includes a conductor 74, a normally open switch which is contained in a water-tight housing 76, and a conductor 78 which is connected to ground through solenoid winding 70. The housing 76 carries an external arm 82 on which a lever 84 is pivoted. The lever carries at one end a float 86, and at the other

end a switch actuating projection 88 which acts through a water-tight rubber cap 90 of the housing 76 to close the switch within the housing when water reaches a predetermined level in the normally dry bottom of the compartment.

While the control system described provides means for automatically opening valve 34 in response to the rising water, and for opening the valve manually from a remote control station, it is also possible manually to engage and actuate the solenoid armature for opening the valve.

In FIGURE 4 a multiple unit system is shown in which, by way of illustration, three of the flotation units are provided, each individually operable from a remote control station, all operable in unison from said station, and each operable automatically through its individual water level control switch. In the main, the circuits for each solenoid winding, on an individual basis, are the same as those described for the single unit system of FIGURE 1, and the same reference numerals have been applied to corresponding parts, but with the letters *a* and *b* added, respectively, to the circuit elements associated with the second and third units.

At the same remote control station at which switches 66, 66*a* and 66*b* are located, a common switch 22 is provided for simultaneously opening the supply valves of all three units. The input side of switch 92 is connected to the conductor 62, and the switch is adapted to be manually closed simultaneously on terminals 94, 94*a* and 94*b*, the terminals being connected, respectively, through conductors 96, 96*a* and 96*b* with conductors 68, 68*a* and 68*b*.

The only part of a flotation unit which has a specific gravity substantially greater than one is the tank 18, and it may be very small in size. Carbon dioxide in liquid form has a specific gravity of 1.1 and hence two liters would weigh 2,200 grams. Since the molecular weight of the gas is 44, the gas weighs a little less than two grams per liter, and two liters of the liquid would provide 1,000 liters of gas at atmospheric pressure, enough to provide 1,000 kilograms of buoyancy.

The problem of bladder and envelope strain is quite complex, involving many factors.

If a bladder is inflated only to, or slightly above, atmospheric pressure, it will be placed under little or no strain prior to submersion or partial submersion. This is frequently desirable, wherever practicable, because a unit inflated substantially above atmospheric pressure will generally be placed under greatest strain either in the course of submersion or before it ever comes into contact with the water. Units are preferably not installed deep in the hold of a ship, in such locations and under such conditions that they would be likely to interfere with the inherent stability of the ship, tending to induce overturning as the ship rolls in a storm, or to establish and maintain a list. In most situations the units are most advantageously installed not substantially below the normal line, and preferably higher in the craft than the normal water line.

The regulator should generally be set to limit inflation to a pressure not very much above atmospheric pressure, and the relief valve should be set to let off gas only at a pressure somewhat above that for which the regulator is set. The higher setting of the relief valve is necessary in order to avoid the wasting of gas. The pressure within the bladder will vary as the craft rolls and pitches, being increased as the unit is forced under the water, and there should not be a discharge of gas, followed by replenishment, every time such an increase occurs.

Although increased pressure of the gas is necessarily attended by a reduction of volume, submersion of the bladder does put the bladder and envelope walls under tensile strains. This is true because a sphere has less surface area than any other solid figure. Inflation of any balloon-like structure bulges the sides, straining them

toward spherical form. Forcing a bulged side to a flat condition contracts the volume of the bladder and thereby compresses the gas.

The strengths of the bladder and the envelope materials can be chosen to meet particular needs, but in the interest of economy no heavier gauge materials should be employed than are practically necessary to make due allowance for deterioration with age, and to provide a reasonable factor of safety. The units should be checked periodically, according to a rigid schedule, as a matter of course.

The shape of the envelope has a bearing upon the strain to which the bladder and the envelope are subjected. The greater the internal thickness between the upper and lower walls of the inflated bladder, the greater will be the potential buoyancy in relation to the horizontal cross-section of the inflated bladder, and the greater will be the pressure per square inch tending to burst the bladder and to rupture the envelope.

To illustrate, we may assume that in a particular case a potential buoyant force of one thousand kilograms is required of a unit. If the envelope were made cubical in shape, measuring one meter along each edge, it would exert a total upward thrust of one million grams when fully submerged, on a horizontal surface of 10,000 square centimeters, or one hundred grams per square centimeter, about one-tenth of an atmosphere. The internal pressure applied equally in all directions within the bladder would then exceed the external atmospheric pressure by, roughly, ten percent. This would mean, however, that the volume of the gas within the bladder has been reduced by deformation of the bladder to about ninety percent of the initial volume of the inflated bladder, with an over-all contraction of the bladder. There would be increased tension, chiefly in those portions of the bladder not yet submerged, caused by the fact that the bladder would be forced to a flattened-out condition, with loss of volume.

If, however, the thickness or depth were divided by four and the horizontal cross-section were multiplied by four, the volume would still be the same as before, and the potential buoyancy would remain unaltered, but the total buoyancy would be distributed over four times as much horizontal area and would amount to only twenty-five grams per square centimeter, increasing the internal pressure by only 2.5 percent. The longitudinal and transverse strains would have this new value per square centimeter, and would be proportional in total amounts to the transverse and longitudinal vertical cross-sectional area, respectively. The tensions in the materials produced by these strains would, therefore, be reduced by making the length and width substantially greater than the thickness.

The foregoing discussion would be strictly true for a static condition of the craft on an even keel. As the craft rolls and pitches, the horizontal projection of the bladder and envelope is diminished, and this causes an increase of pressure within the bladder. When free portions of the bladder stand higher than the carrier attached portions of the envelope, and higher than the bladder neck, tension is necessarily created in the bladder and envelope walls. These considerations must be taken into account in the design of the unit.

Since a unit can be very quickly installed and can be manually tripped, it may be possible in some instances, even after the craft is in serious trouble, for reserve units to be installed and tripped where, for any reason, such as lack of foresight, or collision damage to installed units, reserve units are found to be especially needed.

In accordance with the showing of FIGURE 5, the carrier member of an inflation unit may be clamped by quickly detachable clamping means to the underside of a seat 98 of an open boat. The unit in such a case may be like that of FIGURE 1, but relatively small, and the automatic and remote control means may be omitted.

It is advantageous to provide the clamps 100 on the

seat 98 for detachably clamping the carrier 16 of the inflation unit under the seat, so that the unit can be detached and kept under lock and key when the boat is left moored in the water or is left exposed outdoors. The unit can, of course, be made of a size appropriate to the use for which it is intended.

FIGURE 5 is simply illustrative of the use of any suitable clamping means, affixed either to any convenient and useful part of the boat, or to the carrier member of the flotation unit, for quickly and conveniently attaching the unit to, and removing it from, the boat in any suitable location.

I have described what I believe to be the best embodiments of my invention.

I claim:

1. A flotation unit adapted for compact and inconspicuous mounting in a compartment of a boat or other craft which the unit is designed to help in keeping afloat in an emergency, comprising, in combination,
  - (a) a rigid carrying and mounting member,
  - (b) a metallic tank for containing and making available an inflating gas under high pressure,
  - (c) an inflatable bladder of highly resilient, stretchable material,
  - (d) connecting means providing a channel of communication between the tank and the interior of the bladder, including a supply valve and a pressure regulator, the latter for limiting inflation of the bladder to substantially a predetermined pressure,
  - (e) a protective envelope of strong, tough, flexible, inextensible, woven fabric enclosing the bladder for protecting it against puncture, and for limiting expansion of it to prevent the occurrence of bursting strain, and
  - (f) an easy-tear container surrounding the envelope and normally maintaining the bladder and the surrounding envelope in compactly folded form, but incapable of resisting inflation of the bladder substantially when inflation is initiated,
- the envelope and container having portions which are fixedly secured to the rigid carrying and mounting member, and the construction and ar-

angement being such that the bladder and envelope, though normally confined by the container, are readily freed by it to unfold and expand to the limits prescribed by the envelope in response to inflating pressure.

- 5 2. A flotation unit as set forth in claim 1 in which the bladder is of rubber, the envelope is of woven nylon, and the container is of a less substantial material than either of these.
- 10 3. A flotation unit as set forth in claim 1 which further includes a pressure limiting relief valve in direct communication with the interior of the bladder.
- 15 4. A flotation unit as set forth in claim 1 in which the means connecting the tank with the bladder includes a further channel of communication, in addition to the one containing the supply valve, in which is included a heat responsive, alternative supply valve for turning on the gas supply automatically in case of fire.
- 20 5. A system employing a unit as set forth in claim 1 which further includes means for turning on the supply valve of the unit automatically in response to rising water level within the craft.
- 25 6. A system employing a plurality of units as set forth in claim 1 which further includes means for individually turning on the supply valves of the units by remote manual control from a common control station.
- 30 7. A system as set forth in claim 6 which further includes means for turning on the supply valves of a plurality of the units simultaneously by remote control from the common control station.
- 35 8. A flotation unit as set forth in claim 1, in combination with quickly detachable, attaching means for securing the unit to a selected portion of the craft.
